UNITED STATES PATENT OFFICE.

HENRY E. NIESE AND GEORGE DINKEL, OF JERSEY CITY, NEW JERSEY, AS
SIGNORS TO THE F. O. MATTHIESSEN & WIECHERS SUGAR REFINING
COMPANY, OF SAME PLACE.

APPARATUS FOR COOLING SUGAR.

SPECIFICATION forming part of Letters Patent No. 296,040, dated April 1, 1884.

Application filed May 28, 1883. (No model.)

To all whom it may concern:

Be it known that we, HENRY E. NIESE and GEORGE DINKEL, of Jersey City, New Jersey, have invented a certain Improvement in Apparatus for Cooling Sugar, of which the following is a specification.

Our invention is especially designed to effect the expeditious cooling of soft sugar immediately after its discharge from the centrifugal machines in which it is drained. To that end we provide a suitable arrangement of conveying devices, by means of which the sugar received from the centrifugal machines is conducted to and discharged upon a scattering wheel arranged within a suitable chamber, from which the sugar falls by its own gravity through a pipe, into the lower part of which there is introduced from an adjustable nozzle a strong blast of cold air, which performs the double function of driving the falling sugar onward with accelerated velocity and of cooling the sugar, with the particles of which it is thus brought into contact. To facilitate the distribution of the sugar thus cooled, it is driven by the blast of air into a movable inclined chute, by the manipulation of which the stream of cooled sugar may be given the various directions required to enable it to be thrown into different bins or receptacles.

The accompanying drawings of apparatus illustrating our inventions are as follows:

Figure 1 is a vertical section of portions of several floors of a building containing our apparatus, so arranged that the sugar discharged from the centrifugal machines upon one floor is carried up to a higher floor, and thence permitted to fall until it reaches the bins in which it is deposited after it is cooled. Fig. 2 is a top view of a twin screw-conveyer by means of which the sugar is carried forward to a belt elevator. Fig. 3 is a section upon an enlarged scale of a swiveling pipe, nozzle, and chute into which the sugar falls from the pipe leading from the chamber into which it is delivered by the elevator. Fig. 4 is a top view, showing the bottoms of the receiving-bins and the twin screw-conveyers by which the sugar in them is forced toward the discharge-hole,

through which it falls upon the usual crushing-rollers.

In the structures exhibited in the drawings a row of centrifugal machines, A A, is arranged over the row of chutes *a*, which discharge the sugar from the centrifugal machines upon the endless belt B, by which the sugar is carried horizontally forward and dropped into the trough C, in the bottom of which there is arranged a horizontal conveyer composed of twin screws D and *d*, which rotate in opposite directions, and which are respectively provided with right-hand and left-hand screw-blades. The stems of these screws extend outside the end C' of the trough, and are provided, respectively, with the gears D' *d*', which mesh into each other. Power to rotate the screws D and *d* is transmitted from a suitably placed shaft to the pulley C'. By the operation of these screws the sugar is pushed into the inclined pipe E, by which it is conducted to the bottom of the case F of the belt-elevator G. By the use of the twin screws rotating in opposite directions, having their opposed peripheries moving upward, the sugar in the trough C is prevented from arching, and by properly regulating the speed of rotation of the twin screws the quantity of sugar delivered to the elevator is graduated with reference to the capacity of the elevator to carry it upward from the bottom of the case F.

If desired, there may be arranged within the pipe E the pair of crushing-rolls *e*, driven by power transmitted from the shafting in any convenient manner.

The belt-elevator G is provided with suitably-formed buckets, in which the sugar is carried upward from the bottom of the case F to the top, where it is discharged into the inclined pipe H, from the lower end of which it falls upon a scattering-wheel, I, which is rotated with sufficient velocity to scatter the sugar falling upon it in the chamber J. The chamber J is the tunnel-shaped mouth of the inclined pipe K, down which the sugar falls by its own gravity, and from the lower end of which it is discharged into the swiveling tube L, the lower end of which is bent to an angle

of forty-five degrees, (more or less,) and deposited in the upper end of the chute M. A powerful blast of cold air is conducted to and discharged in a downward direction into the 5 inclined lower end of the tube L by the goose-neck pipe N, the lower end of which loosely surrounds the upper end of the air-service pipe O, and is provided with a bearing upon the table N'. The lower end of the goose-neck 10 N is in vertical alignment with the upper part of the tube L. The chute M is supported by the braces M' and M'', which are affixed to the collar M', surrounding the lower end of the goose-neck. By this construction the tube L 15 and chute M and the goose-neck N have a common vertical axis of rotation. The cold-air blast is supplied to the air-service pipe O by means of a suitable blower, O'.

The drawings represent four receiving-bins, 20 P P' P'' P''' adjoing each other, with the swiveling goose-neck and chute so arranged above them as to permit the sugar to be discharged into either one by turning the goose-neck and chute upon their vertical axis. In 25 the drawings the vertical section of the receiving-bins is taken through the line x x in Fig. 4, and thus shows in elevation the two twin screw-conveyers Q and Q', which are employed to force the sugar from the bins P'' and 30 P''' to the discharge-opening R. Similar twin screw-conveyers are provided for the same purpose at the bottoms of the bins P and P'. A portion, S, of each of the outer sides of the bins P P' P'' P''' is inwardly and downwardly 35 inclined, as shown.

A pair of crushing-rollers, T, may, if de-

sired, be arranged in the usual manner immediately beneath the discharge-opening R, for the purpose of crushing the sugar discharged from the receiving-bins.

40

We claim as our invention—

1. The herein-described apparatus for hastening the cooling of soft sugar immediately upon its discharge from the centrifugal machines, which consists of suitable carrying devices for conducting the sugar as it is discharged from the centrifugal machines into the upper end of a pipe, down which it falls by its own gravity, and into which there is introduced a downwardly-directed blast of 45 cold air, the lower end of said pipe having connected with it a suitable chute, by means of which the sugar falling through the chute by its own gravity and under the influence of the blast of air may be thrown at will in different directions or into different bins, as 50 shown.

2. In combination with apparatus for expeditiously cooling soft sugar immediately upon its discharge from the centrifugal machine, 55 substantially such as described, the carrier-belt B, the trough C, the twin screws D d, and the pipe E, the belt-elevator G, and the inclined pipe H, for conducting the sugar into the elevated chamber J, from which it falls by 60 its own gravity through the pipe K.
